UNITED STATES PATENT OFFICE.

DAVID G. McCAA, OF LANCASTER, PENNSYLVANIA.

CONTROLLING APPARATUS FOR WIRELESS TELEPHONE SYSTEMS.

1,304,188.

Specification of Letters Patent. Patented May 20, 1919.

Application filed June 4, 1918. Serial No. 238,176.

To all whom it may concern:

Be it known that I, DAVID G. McCAA, a citizen of the United States, residing in Lancaster, Pennsylvania, have invented the Controlling Apparatus for Wireless Telephone Systems, of which the following is a specification.

As is known to those skilled in the art of radio telephony, if a source of persistent electrical oscillations of high frequency be electrically coupled to a radiating circuit, the placing of a microphone either in the generating or in the radiating circuit renders it possible to modulate the energy continuously radiated by and in accordance with sound. Generators of persistent oscillations such as the oscillatory arc, when employed in radio telephony, cause more or less objectionable hissing sounds, in addition to those caused by the sound-actuated transmitting mechanism, to be heard at the receiving station, due to the superposition of the variations in the radiated current resulting from such generators, upon the variations caused by the sound actuated mechanism. The sounds referred to are constantly heard between the sound signals or words and in some cases are of such intensity as to interfere with the clear reception of the transmitted sound. One object of my invention therefore, is to provide a system or combination of apparatus of the general character indicated, which shall be so designed and assembled that there shall be none of the above noted objectionable noises in the receiving instrument and in which only sound modulated energy will be radiated.

It is further desired to provide a system of the above type which shall include a novel arrangement of apparatus whereby a given antenna current is modified by and in accordance with current variations in a microphone circuit, so related to or associated with the antenna circuit that the current in the former may be materially less than has hitherto been considered permissible in order to attain the desired results.

These objects and other advantageous ends I attain as hereinafter set forth, reference being had to the accompanying drawings, in which—

Figure 1 is a diagrammatic illustration of the preferred arrangement of apparatus constituting my invention; and

Figs. 2 and 3 are fragmentary diagrams illustrating modifications of my invention.

In the above drawings, 1 represents a high frequency alternating current generator in whose circuit is connected a primary transformer winding 2 which with it is so designed as to constitute a primary source of persistent high frequency oscillations. Inductively associated with this primary winding is a secondary winding 3 forming part of an open radiating circuit consisting of an antenna in the form of elevated conductors 4, a variable inductance 5, and the earth plate or ground connection 6. In addition to the secondary winding 3, there is a connection between the inductance 5 and the ground connection 6 including a second adjustable inductance 7.

This latter inductance serves as the primary winding of a transformer having two secondary windings 8 and 9 of the same number of turns and each adjustable as to the number of turns in circuit. The first of these secondary windings 8 is connected in a closed circuit including a body 10 of non-inductive resistance and an inductance 13, while the second winding is similarly connected in a closed circuit including a microphone 11 and an inductance 12. The two coils 12 and 13 are inductively associated and are adjustable so that they both have the same number of turns under any given operating conditions.

Disregarding for the time being the elements 7—11 with their associated circuit connections, it will be noted that by adjustments of the inductance values of the elements 2, 3 and 5, the open radiating system may be caused to absorb energy from the primary source 1—2 and to radiate it into space. At any given wave length, this function is a maximum when a hot wire or thermocouple meter gives the highest reading.

If when the system is adjusted for maximum radiation at a given or selected wave length, the inductance coil 7 be connected across or in shunt to that portion of the antenna system which is receiving energy from the primary source of supply, *i. e.*, the secondary winding 3, there will be but little change in the current flow provided the reactance value of the inserted inductance is sufficiently high to cause the antenna oscillations to follow the path 4—5—3—6 rather than the path 4—5—7—6. Any slight change in the radiated wave may be compensated for by varying the value of the inductance 5, although if the reactance of the coil 7 is

too small, the radiated wave will be of a reduced length and the coupling of the antenna system with the primary winding will not be so close as heretofore.

5 Obviously if a secondary circuit should be closely coupled to the inductance 7 and if said circuit should be closed, the reactance value of said coil 7 will fall as a result of the counter-action of its magnetic field by 10 the secondary current. With the reactive value of the coil 7 thus practically eliminated, the shunt path in which it is included presents but a low ohmic resistance and consequently acts as a short circuit 15 across the secondary coil 3, cutting off the radiating circuit from the source of supply and causing the antenna current to fall to practically zero. Even if a feeble antenna current should flow through the circuit 20 4-5-7-6, the slight radiation resulting would be at a materially reduced wave length.

A variation of the current in the closed secondary system associated with the inductance 7 causes the antenna current to 25 divide between the circuits 4-5-3-6 and 4-5-7-6, so that the energy from the primary source 1-2 is admitted to or cut off from the antenna to a varying degree depending upon the rise and fall of the current in the secondary circuit which varies 30 the reactance value of the coil 7. The introduction of resistance into the secondary circuit associated with the coil 7 reduces the 35 secondary current, permits the reactance of the coil 7 to increase and causes said coil to fail to short circuit the secondary coil 3, admitting energy from the primary source of supply into the radiating system 40 and altering the effective inductance of the antenna circuit. As a result the antenna system is brought to a natural period corresponding with the maximum radiation and the antenna current will therefore increase in value. Vice versa, decreasing the 45 resistance of the secondary circuit associated with the coil 7 will operate to reduce the antenna current by a reversal of the operations outlined above.

50 If a microphone be connected in the secondary circuit associated with the coil 7, as has been described and claimed in an application for United States Patent filed by me under date of June 13, 1916, Serial No. 55 103,452, I have found that only a voice modulated current is admitted to the antenna.

If as shown in Fig. 1, there are associated with the inductance or primary coil 7 the 60 two secondary coils 8 and 9, closely coupled to it and having the same number of turns, then said coils if connected in closed circuits, will have equal currents induced in them regardless of whether the number of 65 secondary turns in each coil is less or more

than that of the coil 7. Obviously if the circuits of these coils 8 and 9 are otherwise independent, the opening of one of them will allow the other to absorb all of the energy from the primary coil. If however, 70 as shown in Fig. 1, said circuits are inductively and closely coupled by means of the two inductance coils 12 and 13, there is the same division of primary energy between them provided there is a reciprocal 75 counteraction of said coils by reason of the current flow through them and this will depend upon the circuit arrangement or manner of connecting them to the secondary circuits. 80

If one secondary circuit, for example that of the coil 8, be opened, the current in the other will at once drop practically to zero for the reason that the inductance 13 fails to counter-act the reactance of the coil 12, 85 which is of such design as to completely block or choke off the current normally flowing in the circuit of the coil 9 when the circuit of the coil 8 is closed. The same action will result if the circuit of the coil 9 90 be opened, for then the coil 12 fails to neutralize the reactance of the coil 13 and this, as in the first case, chokes off the current flow in the coil 8.

Any decrease of the current in the circuit 95 8-10-13 will cause the reactance value of the coil 12 to increase because of the failure of the inductance 13 to completely counteract it, and there will consequently be a decrease of the current in the secondary circuit 9-11-12, the action being reciprocal 100 between the two circuits. There is therefore, a series effect in the paralleled secondary circuits, since decrease of current in one, instead of causing an increase in the other as 105 is usual in paralleled circuits, will cause a decrease in current and vice versa. The microphone 11 in the circuit 9-11-12 will thus cause variations in the reactance value 110 of the coil 7 under operating conditions, although it is noticeable that this result is attained by the direct modulation of but a part of the total energy supplied from said coil. 115

By repeated experiments I have found that the antenna current will not rise nor increase in value until more than a certain resistance is inserted in one of the secondary circuits, for example 8-10-13, and since the current normal to these circuits is 120 reduced by this inserted resistance, but a fractional part of such current is required to maintain the antenna current practically zero. As a result of this arrangement which involves the non-inductive resistance 10, the 125 microphone is called on to modulate current values materially less than have hitherto been found practicable. That is to say, modulation of the reduced current in the circuit 9-11-12 will cause complete modu- 130

- lation of all the energy available in the antenna circuit, the antenna current rising and falling with the increase and decrease of resistance in the microphone. As an example
- 5 I have found that antenna currents of ten amperes have been modulated fully when a current of one and one-half amperes was present and modulated in the microphone circuit.
- 10 It will be understood that without departing from my invention, the resistance 10 of the system shown in Fig. 1, instead of being inserted in but one of the secondary circuits, may be divided and one part 14 be connected 15 in the circuit 8—13 while the other part 15 is connected in the secondary circuit 9—12. Similarly, instead of a single microphone in one of the secondary circuits, there may be two microphones 11 and 11^a connected respectively in the circuits of the two secondary coils 8 and 9. It is to be noted that the 20 transformation ratio between the coil 7 and the coils 8 and 9 may be either step-up or step-down, although I prefer the step-down ratio as this permits lower voltages in the microphone.
- If it be desired to still further reduce the current flow in the microphone circuit, I 25 may substitute for the microphone in the circuit 9—12—11 an inductance 16 of such value as to be capable of completely blocking the flow of current in said circuit. It is then possible to associate with this inductance two other inductive windings 17 and 30 18, of which the first is included in a circuit having also connected in it a fixed non-inductive resistance 19 and an inductance 20 operatively associated with an inductance 21 included in circuit with the coil 18 and a 35 microphone 22. The action of the system comprised by the circuits 17—20—19 and 18—21—22, upon the coil 16 and the circuit of which it forms a part, is similar to that 40 previously described in connection with the arrangement illustrated in Fig. 1, and as 45 above indicated, the relatively small current flow in the circuit 18—21—22, which is modulated or varied by and in accordance with the sound waves acting on the microphone, acts upon and causes corresponding 50 variations of the much greater current of the antenna circuits—and that without causing or involving the objectionable hissing sounds in the receiving apparatus which 55 would otherwise be present.
- By these means there is admitted to the antenna only sound modulated current whose envelop curve presents steep variations in amplitude which extinguish by the sound 60 produced in a receiver, the slight variations due to irregularities in the generator.
- I claim:
1. The combination in a transmitting system of a branched radiating circuit; a source of high frequency oscillations opera- 65
- tively connected to one branch of said circuit; a primary transformer winding connected in the other branch of the radiating circuit; a plurality of auxiliary circuits each including a secondary winding inductively 70 associated with said primary winding; means operatively associated with one of said auxiliary circuits for varying the current flow therein by and in accordance with sound; and means independent of said secondary windings for inductively connecting 75 said auxiliary circuits.
2. The combination in a transmitting system of a radiating circuit; a source of high frequency oscillations operatively connected 80 to said circuit; two inductively coacting auxiliary circuits also connected to said circuit; with means operatively connected to one of said auxiliary circuits for modulating the current flow therein by and in accordance with sound.
3. The combination in a transmitting system of a radiating circuit; a source of high frequency oscillations operatively connected 85 to said circuit; two inductively coacting auxiliary circuits inductively connected to said first circuit; and a microphone connected in one of said auxiliary circuits.
4. The combination in a transmitting system of a radiating circuit; a source of high 90 frequency oscillations operatively connected to said circuit; a primary transformer winding also connected in said circuit; a plurality of auxiliary circuits respectively including secondary windings coacting with 95 said primary winding; means connected in one of the auxiliary circuits for causing the current flow therein to be varied by and in accordance with sound; and means for causing the currents in the auxiliary circuits to 100 rise and fall simultaneously.
5. The combination in a transmitting system of a branched radiating circuit; a source of high frequency oscillations operatively connected to one branch of said circuit; a primary transformer winding in the other branch of said circuit; a plurality of auxiliary circuits respectively including secondary windings coacting with 105 said primary winding; means connected in one of the auxiliary circuits for causing the current flow therein to be varied by and in accordance with sound; and means consisting of coacting inductances respectively connected in said circuits for causing the currents 110 therein to rise and fall simultaneously.
6. The combination in a transmitting system of a radiating circuit; a source of high frequency oscillations operatively connected 115 to said circuit; a primary transformer winding also connected in said circuit; a plurality of auxiliary circuits respectively including secondary windings coacting with said primary winding and designed in step- 120 down ratio thereto; means for modulating 125
- 130

the current flow in one of the auxiliary circuits by and in accordance with sound; and means independent of the secondary windings for causing said auxiliary circuits to 5 mutually react one upon the other.

7. The combination in a transmitting system of a radiating circuit; a source of high frequency oscillations operatively connected to said circuit; a primary transformer winding 10 also connected in said circuit; a plurality of auxiliary circuits respectively including secondary windings coacting with said primary winding; a resistance in one of the auxiliary circuits; means connected 15 in the other circuit for modulating the current flow therein by and in accordance with sound; and coactive inductances respectively connected in the auxiliary circuits.

8. The combination in a transmitting system of a radiating circuit; a source of high frequency oscillations and a primary transformer winding operatively connected to 20 said circuit; a plurality of auxiliary cir-

cuits inductively associated with said primary winding; means for causing current 25 flow in the auxiliary circuits to simultaneously and equally rise and fall; and means for causing the current flow in the auxiliary circuits to be varied by and in accordance with sound.

9. The combination in a transmitting system of a radiating circuit including a primary transformer winding; a plurality of auxiliary circuits respectively including 30 secondary windings inductively associated with said primary winding; means independent of said windings for causing current flow in one of the auxiliary circuits to vary directly as the current flow in the other auxiliary circuit is varied; and means for 35 modulating the current flow in one of the auxiliary circuits by and in accordance with sound.

In witness whereof I affix my signature.

DAVID G. McCAA.
